UNITED STATES PATENT OFFICE.

JOHN B. FREYSINGER, OF NEW BRITAIN, CONNECTICUT.

FLEXIBLE CLOSURE.

Application filed June 22, 1926. Serial No. 117,872.

This invention relates to flexible closures of the type having a pair of stringers or tapes provided on their opposed edges with clasps or locking members which are adapted to be successively brought into interlocking relation when a slide is moved longitudinally of the tapes in one direction and which are disengaged when the slide is moved in the opposite direction.

The object of the invention is to provide a flexible closure of this sort having improved interlocking members which are very simple in construction, which may be economically manufactured, and which are effective in operation. The construction of the locking members is such that they may be uniformly made from sheet metal and, when in interlocked condition, they form a secure and tight closure.

Other objects will be in part obvious and in part pointed out more in detail hereinafter.

The invention accordingly consists in the features of construction, combination of elements and arrangement of parts which will be exemplified in the construction herein-after set forth, and the scope of the application of which will be indicated in the appended claims.

In the accompanying drawings, wherein I have shown, for illustrative purposes, two embodiments which the present invention may take:

Figure 1 is an elevational view showing the complete assembly;

Fig. 2 is a sectional view taken on line 2-2 and looking in the direction of the arrows associated with that line;

Fig. 3 is a perspective view of one of the locking members of the assembled structure shown in Fig. 1;

Fig. 4 is a plan view of the pierced and sheared flat blank from which the locking member of Fig. 3 may be formed;

Fig. 5 is an enlarged detail view showing a number of these locking members or clasps in interlocking relation, the two lower locking members being shown in longitudinal section;

Fig. 6 is a view similar to Fig. 5 but showing the interlocking members of a different embodiment;

Fig. 7 is a perspective view of one of the locking members of Fig. 6; and

Fig. 8 is a plan view of the pierced and

sheared blank from which the locking member of Fig. 7 may be constructed.

Referring to the drawings in detail, *a* and *b* denote the respective stringers or tapes; *c*, *c* designate the locking members of the series secured to the tape *a*; and *d*, *d* designate the locking members of the series secured to the edge of the stringer *b*. *e* is a slide for engaging and disengaging the locking members. This slide may be of any suitable construction, the particular form and arrangement thereof forming no part of the present invention. *f* designates a bottom stop of any suitable construction for limiting the opening movement of the slide, and *g*, *g*, top stops which may also be of any suitable construction for limiting the closing movement of the slide.

In the present illustrative disclosures of the invention, the locking members of both series are preferably of identical construction so as to effect economy in manufacture, and each locking member is adapted to be interlocked with a superimposed locking member and a subjacent locking member of the opposite series.

Referring to the embodiment shown in Figs. 1 to 5, inclusive, each of the locking members is preferably constructed by stamping out a blank from sheet metal, although, of course, it is to be understood that the locking members may be constructed of material other than sheet metal. The form of the stamped out blank is shown in Fig. 4. This blank has, at its rear or attached end, a pierced opening 10 and a slot 11 leading thereto so as to form a pair of wings or jaws 12. The opening 10 is adapted to receive a bead of a stringer, and the jaws are adapted to be forced together so as to securely clamp the locking member in place. At the forward or free end of each locking member are a pair of longitudinally extending slits 13 which divide the forward end of the locking member into three fingers, the central finger 14 and two end fingers 15 of greater length than the central finger 14. The end fingers 15 are bent into angular shape so that each finger has a V-shaped pocket 16 on its under side and a rounded hump or projection 17 on its upper side. The pockets 16 of the two end fingers are separated by the middle finger or lug 14 which is in the plane of the body portion of the locking member. The pockets 16 pref-

erably have sharp V-shaped bottoms, as shown in the drawings.

The locking members *c* and *d* are assembled on the stringers in staggered relation, as shown in Fig. 1. From this figure, it will be seen that, when the fastening device is closed, the V-shaped pockets 16 of each locking member receive the respective humps or projections 17 of the next subjacent locking member. The lug 14 of each locking member engages between the humped up fingers of the next subjacent locking member so that the locking members are held against relative lateral movement. It will further be seen, particularly from Fig. 1, that, when the locking members are moved into or out of locking engagement, they have a proper camming action relative to one another, which results in a smooth and easy operation. It is clear that each of the locking members is very simple in construction and can be very cheaply manufactured, while, at the same time, they are accurate and uniform in all respects, all of which means that a fastening device constructed in accordance with the present invention may be manufactured at a low cost, while, at the same time, a high degree of effectiveness in operation is obtained.

Referring now to the embodiment shown in Figs. 6 to 8, inclusive, the locking members *c'* and *d'* may be each made by stamping a blank from sheet metal as in the preceding embodiment. The blank from which a locking member of this embodiment may be formed is shown in Fig. 8 and has pierced therein an opening 10' and a slot 11'. The forward end of the blank is longitudinally slit or sheared, as at 13', so as to provide a central locking lug or finger 15' and a pair of end lugs 14', the end lugs being preferably shorter than the middle finger. The middle finger is bent up in the same manner as are the fingers 15 of the preceding embodiment so as to provide a pocket 16' and a hump or projection 17'.

The manner in which the locking members, constructed in accordance with the showing in Fig. 7, interlock is clearly disclosed in Fig. 6, and it will be seen from this figure that the pockets 16' of each locking member receive the hump or projection 17' of the next subjacent locking member of the opposite series, and that the locking finger 15' of each locking member is straddled by the lugs 14' so that the locking members, when in interlocked condition, are maintained in the correct relation to one another.

As many changes could be made in the

above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A locking member for flexible closures of the character described having a body portion provided at one end with means for securing the same to a flexible tape, and a plurality of longitudinally extending fingers at its opposite end, one at least of said fingers having an angular or V-shape to provide a pocket and a locking projection, one at least of said fingers being in the plane of the locking member and closing one end of said pocket.

2. A locking member for flexible closures of the character described, having at one end means for securing the same to a flexible tape and at its other end three fingers, two of said fingers being of a length different from the third one and the longer of said fingers being bent in an angular or V-shape, the shorter of said fingers being in the plane of the body portion of the locking member.

3. A locking member for flexible closures of the character described formed by stamping out a pierced blank having a pair of slits at one end to provide three fingers, the middle of said fingers being of lesser length than the end ones, said end fingers having a V or angular shape so that each end finger provides a V-shaped pocket and a hump or projection, the middle of said fingers being disposed between said pockets.

4. A flexible closure of the character described having a pair of flexible stringers and a series of locking members on each stringer, said locking members being staggeredly arranged and each having at its free end a plurality of fingers, one at least of said fingers of each locking member being bent into V or angular shape to provide a pocket and a projection, and one of the fingers of each of said locking members constituting a lug in the plane of the locking member.

JOHN B. FREYSINGER.
